UNITED STATES PATENT OFFICE.

ROY N. COATS, OF MARSHALLTOWN, IOWA.

THERMOSTATIC FAN.

1,267,975.

Specification of Letters Patent. Patented May 28, 1918.

Application filed June 3, 1916. Serial No. 101,512.

To all whom it may concern:

Be it known that I, Roy N. Coats, a citizen of the United States, and a resident of Marshalltown, in the county of Marshall and State of Iowa, have invented a new and Improved Thermostatic Fan, of which the following is a full, clear, and exact description.

The object of the invention is to provide 10 a new and improved thermostatic fan more especially designed for use on automobiles and similar vehicles for controlling the air circulated through the radiator to maintain the water in the radiator at a desired temperature.

In order to accomplish the desired result, use is made of a fan wheel having vanes mounted to turn and thermostatically controlled means mounted on the fan and connected 20 with the said vanes for turning the latter into a more or less open or closed position according to the temperature of the surrounding atmosphere.

A practical embodiment of the invention 25 is represented in the accompanying drawings forming a part of this specification, in which similar characters of reference indicate corresponding parts in all the views.

Figure 1 is a face view of the thermostatic fan with parts shown in section;

Fig. 2 is a longitudinal central section of the same; and

Fig. 3 is a sectional plan view of the same.

The head 10 of the fan wheel 11 is mounted 35 to turn on a shaft or stud 12 and on the said hub 10 is secured a pulley 13 connected by belt with other machinery for imparting a rotary motion to the fan wheel 11. It is understood that I do not limit myself to the 40 means shown and described for rotating the fan wheel 11 as other suitable means may be employed. On the hub 10 of the fan wheel 11 are secured radially disposed shafts 15 connected at their outer ends with a rim

45 16, and on the said shafts 15 are mounted to turn loosely vanes 17 of the usual shape. On the inner ends of the vanes 17 are secured bevel pinions or segments 20 in mesh with a bevel gear wheel 21 mounted to rotate 50 loosely on the hub 10. The bevel gear wheel 21 is provided with wings 22 disposed radially and on each wing is secured one end of a thermostatic bar 23 extending with its free end 24 between a pair of pins 25 secured to one end of the driving pulley 13. Each of the thermostatic bars 23 is prefer-

ably made of two superimposed pieces of metal having different coefficients of expansion, the bar being approximately U-shaped, as plainly indicated in Fig. 1, so that the 60 free end of each bar on expanding tends to rotate the bevel gear wheel 21.

When the air passing through or around the fan wheel 11 is cold then the thermostatic bars 23 hold the vanes 17 parallel to 65 the plane of the fan wheel and hence when the fan wheel is rotated it moves no air. When the temperature of the air surrounding the fan wheel 11 rises then the thermostatic bars 23 act on the pins 25 and thereby 70 turn the bevel gear wheel 21 whereby the pinions 20 are rotated and with the same the vanes 17 moving the latter into angular position, thus causing the air to be moved by the revolving fan wheel. The amount of 75 air caused to circulate by the rotating fan wheel 11 is sufficient to maintain the water in the radiator at a desired temperature. When the temperature of the surrounding air decreases then the vanes 17 are correspondingly turned into a position to decrease the pumping action thereof.

From the foregoing it will be seen that by the use of the thermostatically controlled turning means for the vanes the latter are 85 automatically turned into a position to pump more or less air according to the temperature of the surrounding atmosphere.

Having thus described my invention, I claim as new and desire to secure by Letters 90 Patent:

1. A fan comprising a hub, vanes mounted to turn on the said hub, pinions on the said vanes adjacent the hub, a gear wheel mounted to turn loosely on the hub and in mesh with 95 the said pinions, a driving means for the said hub, and thermostatic bars connecting the said driving means with the said gear wheel.

2. A fan, comprising a hub, a driving 100 member on the hub, vanes mounted to turn on the hub, pinions on the vanes adjacent the hub, a gear wheel loosely mounted on the hub and meshing with the pinions of the vanes, and thermostatic bars, connecting the 105 gear wheel and driving member, each thermostatic bar having one end fixedly secured to one of the said parts and its other end loosely secured to the other part.

3. A fan, comprising a hub, a driving 110 member on the hub and having pairs of pins projecting from one end, vanes mounted

to turn on the hub, pinions on the vanes adjacent the hub, a gear wheel loosely mounted on the hub and meshing with the pinions, said gear wheel having radial arms, and thermostatic bars, each having one end secured to an arm of the gear wheel and its other end extending between a pair of pins of the driving member.

4. A fan, comprising a hub, a rim, radial shafts between the hub and rim, vanes mounted to turn on the shafts, pinions on

the inner ends of the vanes, a gear loosely mounted on the hub and meshing with the pinions, said gear wheel having radial arms, a pulley mounted on the hub and having 15 pairs of pins projecting from one end, and thermostatic bars, each having one end secured to an arm of the gear wheel and its other end extending between a pair of pins of the pulley.

ROY N. COATS.
